UNITED STATES PATENT OFFICE.

FRANCIS E. ACKERMAN, OF NEW CANAAN, CONNECTICUT, ASSIGNOR TO JULIUS FORSTMANN & CO., INC., OF PASSAIC, NEW JERSEY, A CORPORATION OF DELAWARE.

IDENTIFICATION DEVICE.

Application filed December 18, 1925. Serial No. 76,156.

This invention relates to improvements in identification devices, and has particular reference to a method of identifying a fabric and to a folder to which the swatch of said fabric is attached.

It is well known, in the textile industries, that unscrupulous dealers have produced and disposed of fabrics and designs thereof of inferior qualities in imitation of the products 10 of high grade manufacturers to the detriment not only of said manufacturers, but also of the public at large. For example, vast quantities of goods are represented and sold as being imported which are, as a matter of fact, of inferior grade and domestic origin.

An object of the present invention is to overcome the difficulties arising from the above mentioned practice by providing an identification device which may be attached 20 to a fabric and which will enable the purchaser of said fabric to determine whether the same is of the quality and design represented by the vendor.

Another object is to provide an identification device in the form of a folder in which a sample or swatch may be secured in such manner as to avoid surreptitious removal thereof and the substitution of another swatch without detection.

The above and other objects will appear more clearly from the following detailed description, when taken in connection with the accompanying drawing, which illustrates a preferred embodiment of the inventive idea.

In the drawing—

Figure 1 is an elevation, partly broken away, of one side of the device;

Figure 2 is an elevational view of the other side of the device;

Figure 3 is a plan view of the device in open position;

Figure 4 is a section on the line 4—4 of Figure 1; and

Figure 5 is a section on the line 5—5 of Figure 1.

The device, which in its preferred embodiment, is shown in the form of a folder made from a single sheet of any suitable material, such as heavy paper or the like. The sheet 50 or body portion is scored transversely intermediate its ends as at 6 to provide the back member 7 and front member 8, the latter being foldable over upon the back member when the folder is closed, as shown in Figures 1 and

55 2. The back member 7 is further scored

transversely and adjacent its free end, as indicated at 9, to provide a flap 10 foldable upon the back member and adapted to receive between the same and said member an edge or end portion of a swatch or sample 11.

Means are provided for securely fastening the swatch 11 to the back member and flap and this means is preferably in the form of fastening devices each of which consists of a base plate 12 having laterally extending 60 prongs or spurs 13 at the ends thereof. In practice each plate 12 is engaged with the outer surface of the back member 7 and the prongs 13 are caused to penetrate said back member, the swatch 11 and the flap 10. A 70 securing plate 14 having a pair of slots 15 adjacent each end is then engaged with the outer surface of the flap 10 with the prongs projecting through certain of said slots. Then by any suitable means the extremities 75 of the prongs are bent in a reverse direction with respect to the remainder of the prongs with said extremities projecting into the adjacent slots 15, as clearly shown in Figure 5, thus locking the plates 12 and 14 together and at the same time firmly securing the swatch to the folder.

In order to prevent surreptitious removal of the swatch from the folder, without detection, the invention further provides a sealing strip 16 made of any suitable material and printed or engraved with an ink which will run or blur upon the application of moisture thereto. This strip 16 is pasted or otherwise firmly secured to the flap 10 in such manner as to cover the plates 14 and the extremities of the prongs 13, as clearly indicated in Figures 1 and 3. In this manner tampering with the prongs 13 in an attempt to remove the fastening devices is prevented unless the sealing strip is removed or defaced, and should it be attempted to displace said strip by the application of moisture this will immediately become evident due to the particular kind of ink with which the strip is printed. It will thus be apparent that from this construction and manner of securing and sealing the swatch within the folder, it will be practically impossible to fraudulently remove the swatch from the folder and substitute another 100 swatch therefor, without detection.

The side edges of the back member 7 are provided with flaps 17 which are foldable inwardly upon the adjacent portions of the swatch 11 with the ends of said flaps adjacent 110

the flap 10 freely engaged beneath the latter so as to retain the flaps 17 in their folded position. When the folder is closed the free end of the front member 8 is inserted between 5 the free edge of the flap 10 and the flaps 17. In this manner the latter flaps will space the major portion of the outer surface of the swatch 11 from the inner surface of the front member or cover 8 and thereby prevent the 10 latter from rubbing off the pile or nap of the fabric, thus insuring that the swatch will at all times have the appearance of the original fabric of which the swatch is a sample.

The outer and inner surfaces of the front 15 member 8 may be provided with suitable indicia to indicate the purpose of the folder to the purchaser of the fabric to which said folder is attached, so that the purchaser of said fabric may examine and compare the 20 fabric with the swatch in said folder and thereby determine the genuineness of the fabric. In this connection, it is evident that the swatch may be inspected by simply opening the folder to the position shown in Figure 3 25 and without the necessity of disturbing the fasteners 12 or the sealing strip 16.

What is claimed is:—

1. In an identification device for fabrics, a body portion including front and back members one of which has a flap at one end under 30 which an edge of a swatch and the free end of the other member are capable of being engaged, means extending through said back member and said flap for securing the swatch thereto, and other flaps on said back member having ends thereof loosely engageable under 35 the first named flap and with portions of said swatch to space said front member from said swatch when the free end of said front member is inserted beneath said first named flap.

2. In an identification device for fabrics, a folder including a back member, means on said member for attaching a swatch thereto, a front member combining with said back member 40 to enclose and cover said swatch and mov-

able to a position to expose said swatch for inspection without disturbing said attaching means, and means carried by said back member for holding portions of the swatch between the same and said member and for maintaining said front member in spaced relation to said swatch when said front member is in covering position. 50

3. In an identification device for fabrics, a folder formed from a single sheet of material 55 and scored to provide front and back members, and a flap at one end of one of said members, said flap being foldable over upon the latter member whereby a swatch may be held between said member and flap, fasteners extending through said flap and said latter member for securing said swatch thereto, a sealing strip attached to said flap and covering portions of said fasteners, other flaps formed along edges of said latter member and foldable over on to said swatch in interposed relation between the swatch and the other member when the latter is in folded position whereby to space the swatch therefrom, the free end of said other member and the ends of said other 60 flaps adjacent the first named flap being loosely engageable beneath the latter to releasably retain said other flaps and member in folded position. 65

4. A device for identifying the quality and 70 design of a fabric, including a body portion to which a swatch of said fabric is attached and which is, in turn, attachable to said fabric to afford comparison between the fabric and swatch, spaced fasteners extending through 75 said body portion and swatch for attaching the same together, and a single sealing strip having one entire surface adhesively secured to the body portion and covering said spaced fasteners, said strip being engraved with an 80 ink affected by moisture so that tampering with said strip may be detected. 85

In testimony whereof I have affixed my signature.

FRANCIS E. ACKERMAN.
